UNITED STATES PATENT OFFICE.

JOSEPH GARDAM, OF BROOKLYN, NEW YORK, ASSIGNOR OF TWO-THIRDS
TO WILLIAM GARDAM AND FREDERICK WILLIAM GARDAM, OF SAME
PLACE.

DIPPING-NEEDLE.

SPECIFICATION forming part of Letters Patent No. 234,110, dated November 2, 1880.
Application filed August 13, 1880. (No model.)

To all whom it may concern:

Be it known that I, JOSEPH GARDAM, of Brooklyn, county of Kings, and State of New York, have invented a new and useful Improvement in Dipping-Needles, which improvement is fully set forth in the following specification and accompanying drawings, in which—

Figures 1 and 2 illustrate different forms of my improved dipping-needle, figures to the right representing vertical transverse sections through the centers of the same.

In using the ordinary dipping-needle it has always been necessary that the person operating the same should be familiar with the direction of the magnetic meridian at that particular spot upon which he is situated, so as to cause the needle to swing in a perpendicular plane passing through the magnetic meridian, thereby to relieve the centers from the greatest amount of friction and to obtain an unincumbered dip of the needle.

My object in said improvement is now to provide a dipping-needle which shall readily indicate the direction of the magnetic meridian, while yet assuming the dip necessarily involved by local or magnetic attraction.

The needle N, Fig. 1, is balanced on its axis between two agate or jeweled centers, J J, the latter being adjustable through opposite sides of the perpendicular slotted support H. This support H is now further provided at each extremity with pivots resting in agate or jeweled centers J J, which are also rendered adjustable in and through the annular body A of the instrument.

It will now be evident that if the instrument be held by the suspensory-ring (indicated as encircling the entire instrument) the needle N will, in assuming the direction of the magnetic meridian, cause the perpendicular support H ⁴⁰ to revolve in its centers J J independent of any dip indicated by possible local or magnetic attraction.

To read the dip it is but necessary to cause the dial or annular body A to swing in the same plane with the needle.

In Fig. 2 I have abandoned the lower pivot and center of the support H and caused the latter to swing upon but one (the upper) pivot and center J by providing a recess, U, at the top of the annular body A of the instrument. (More clearly shown in section.)

What I claim as new, and desire to secure by Letters Patent, is—

1. In combination with a dipping-needle, N, 55 a perpendicular slotted support, H, revolving upon its pivots J J between centers which are rendered adjustable in and through opposite sides of the annular body A of the instrument, substantially as shown and described.

2. In a dipping-needle compass, a needle, N, balanced between adjustable centers J J, in combination with a perpendicular slotted support, H, revolving in and balanced on adjustable centers J J at one or both extremities of 65 said support, substantially as and for the purpose described.

Witnesses: JOSEPH GARDAM.

WALTER LARGE,
FEDERICK BETZ.

Correction for Letters Patent No. 234,110.

It is hereby certified that in Letters Patent No. 234,110, dated November 2, 1880, issued to Joseph Gardam, for Improvement in Dipping Needles, the reference letters J_1 J_1 in lines 33, 41, 57, and 65 of the specification and claims, were erroneously printed J , J , and the reference letter J_1 in line 50 of the specification was erroneously printed J ; that the proper corrections have been made in the records of this Office, and that the said correction is hereby made in said Letters Patent.

Signed, countersigned, and sealed this 20th day of November, A. D. 1880.

[SEAL.]

A. BELL,
Acting Secretary of the Interior.

Countersigned:

E. M. MARBLE,
Commissioner of Patents.
